UNITED STATES PATENT OFFICE.

JOSEPH H. WALSH, OF PELHAM, NEW YORK, ASSIGNOR TO JOHNS-MANVILLE, INCORPORATED, OF NEW YORK, N. Y., A CORPORATION OF NEW YORK.

PROCESS OF ACIDULATING AND CARBONIZING FABRIC WEBS.

Original application filed April 7, 1922, Serial No. 550,537. Divided and this application filed March 16, 1925. Serial No. 16,083.

This invention relates to the treatment of textile fabrics by reagents and heat and to a process useful, for example, in treating textile fabrics by acidulating, drying and carbonizing the fabric to facilitate the removal of vegetable matter therefrom. The present application is a division of my application Serial No. 550,537 filed April 7, 1922, which has matured into Patent No. 1,530,064 dated March 17, 1925.

In the acidulating, drying and carbonizing of fabric as heretofore practiced, little attention has been paid to the matter of economy in the use of heat, although in large cloth finishing establishments the heat wasted in such processes may be a very considerable item of loss. Moreover, as commonly practiced, great difficulty has been experienced in securing uniformity in the product, and in so controlling the carbonization process as to avoid damage to the fabric, by reason of the fact that the energy of action of the acid (or other reagents) employed varies with variations both in the temperature and humidity to which the material is subjected during carbonization. If, on the other hand, but one of such factors is a variable, it is a comparatively simple matter to determine the concentration of the acid by giving to such factor a proper and determinable value. For example, if the material be first acidulated and then dried to a determinate degree, and then immediately subjected to heat in a substantially air-tight enclosure, the concentration of the acid and its action upon the fibres may be controlled exactly merely by regulating the temperature and the time of exposure in such enclosure.

I have found that it is conducive to conservation of heat, to economy in space, to avoidance of repeated handlings of the material, and to the successful avoidance of escaping acid fumes to perform the drying and carbonizing processes in close proximity to each other, or within the same or connected enclosures.

For proper economy in the use of heat I contemplate performing the drying and carbonizing operation within a suitable enclosure of acid resistant material and causing the moisture-laden air within the drying chamber to be discharged therefrom while passing in heat-transferring relationship to

air on its way to such chamber. In the practical realization of the invention, and for further saving of heat, the drying chamber may be disposed between compartments in which a relatively high temperature prevails.

Principal objects of the present invention are accordingly to provide a process whereby fabric webs may be treated with a reagent, dried in a uniform and economical manner, and thereafter heated for the reaction, or carbonized, under accurately controllable conditions.

Figure 1 is a vertical longitudinal section of a housing containing drying and carbonizing apparatus taken on a line such as *a*—*b* of Fig. 2;

Figure 2 is a horizontal section on a line such as *c*—*d* of Fig. 1;

Figure 3 is a transverse vertical section on the line *e*—*f* of Fig. 2;

Figure 4 is a plan view of an acidulating and preliminary drying apparatus useful in carrying the present invention into effect; and

Figure 5 is a side elevation of the devices shown in Fig. 4.

Referring to Figs. 4 and 5, the numeral 1 indicates the usual tank or other suitable receptacle in which dilute acid (or other reagent) may be placed. This tank is provided with a pair of guide rolls 2 and a fabric depressing roll 3, as well as a guide roll 4, such rolls serving to cause the web of fabric 5 to pass downwardly in the liquid contained in the tank and then upwardly therefrom. A drum 6 of relatively large diameter may also be provided, such drum consisting of spaced heads having radial pins or spurs 7 for engagement with the marginal portions of the fabric, such heads being mounted upon a shaft 6^a. A guide roller 8 is arranged adjacent to such drum for causing the web 5 to engage the pins or spurs and after passing around the drum throughout a substantial portion of the periphery thereof, the fabric engages a guide roll 9 spaced somewhat from the roll 8.

Between the rolls 8 and 9 a conduit 10 is arranged through which a current of air, warmed by a heating device 11, may be caused to enter the interior of the drum under suitable slight pressure, as usual. The apparatus thus far described, (which may

be like that of prior knowledge) serves to moisten the web of fabric with acid and then to remove the excess of liquid from the fabric by the exposure of a large area of its surface upon the periphery of the drum to the evaporative action of the air, such action being assisted by the warm air entering the interior of the drum and passing out through the interstices of the fabric. The heat employed in this preliminary drying is insufficient to dry out the moisture or to cause the evolution of acid fumes from the material.

From the guide roll 9 the material passes in contact with rolls 12 and 13 and through a slot 14 in the end wall 15 of a housing, such housing comprising the opposite end wall 16, side walls 17 and 18, and the top or roof 19. The walls and roof of this housing are preferably formed as indicated in section in Fig. 1, consisting of studs or rafters 20 which support an outer sheathing 21 of any desired material, and an inner sheathing 22 of an acid resistant and preferably heat insulating sheet material such, for example, as the asbestos and cement aggregate known as "asbestos wood". If desired, and in order further to prevent the rapid escape of heat through the walls of such housing, the spaces between the inner and outer sheathings may be filled with a heat insulating substance such for example, as asbestos wool, corrugated asbestos board, etc., as indicated diagrammatically at 22^a in Fig. 1.

The space within the housing is divided by means of a vertical partition into a drying chamber 23^a and a carbonizing chamber 23^b. The partition 23 is preferably of acid resistant material, and is provided with an opening 24 at its lower portion for the passage of the web of fabric from the drying chamber in the carbonizing chamber. The end wall 16 of the housing is furnished with a slot 25 for the egress of the fabric, suitable guide rolls such as 25^a being arranged upon the outer surface of such wall, and serving to guide the treated fabric to a winding drum 25^b.

Spaced from the wall 17 of the housing is a partition 26 which serves to define a plenum chamber 43 at one side of the drying chamber, such plenum chamber if desired being furnished with heating coils 27. At the opposite side of the drying chamber, a second partition 27^a is arranged, being spaced from the wall 18 to provide a chamber for the reception of a heat interchange economizer device of suitable construction.

As shown, the economizer comprises transverse end walls 28 and 29 respectively, provided with series of openings in which are fitted the end portions of open-ended tubes 30 which may be molded of asbestos wood, or made of or lined with an acid resistant

material. Interposed between the partitions 28 and 29 are a plurality of baffle plates 31 for determining a flow-path in the chamber exterior to the tubes.

Between the partition 28 and the partition 23 a chamber 32 is provided which communicates with the space between the partitions 26 and 27^a, and which latter space constitutes the drying chamber proper. At the opposite end of the economizer device an educt flue 33 is provided between the partition 29 and the wall 15, leading into the lower end of a pipe 34 having a damper 34^a, this pipe 34 leading to any desired point for the discharge of the acid fumes from the chamber. An inlet opening 35 is provided in the top member 19, such opening providing for the admission of air into the space between the tubes 30, and being located adjacent to one end of the economizer structure. Air from such inlet opening passes about the tubes 30, being directed in a tortuous course by means of the baffle plates 31, and is thence discharged through a pipe 36 which serves to conduct such air to a casing 37. The casing 37 is provided with regulable heating coils 38 whereby the air may be further raised in temperature, and from such casing the air is conducted by the conduit 39 to a fan 40 actuated by a pulley 41 or other suitable means, and from such fan the air is discharged through the conduit 42 into the plenum chamber 43. The temperature of the air in chamber 43 may be further raised, if desired, by the coils 27.

Within the drying chamber two vertically disposed series of guide rolls 44 and 45 are arranged, said guide rolls being so disposed as to cause the fabric 5 passing thereto to extend in a series of vertically spaced horizontal runs. Between adjacent runs of the fabric, series of discharge nozzle tubes 46 are provided, such nozzle tubes preferably being of tapering form, and of acid resistant material such as asbestos wood. Each of these tubes is provided with a discharge slot 47 extending transversely of the width of the fabric, such slots, if desired, being of gradually decreasing width from the larger end of the tube toward the opposite end to provide for laterally uniform delivery. The larger ends of the nozzle tubes, which are open, are fixed in suitable openings in the partition 26, while the smaller ends of such tubes, which are closed, are secured in the partition 27^a. The arrangement of tubes is such as to provide for a substantially uniform discharge of air from the plenum chamber 43 into the spaces between the runs of material and in a direction substantially normal to the surface of the material.

All or a selected number of the rollers 44 and 45 may be actuated by means of

chains such as 45^a extending over sprocket wheels such as 44^b and 45^b arranged within the plenum chamber 43 and fixed upon the ends of the shafts upon which the respective rollers are mounted. The driving connections 45^a are in the fume-free air of chamber 43.

A sprocket 45^c may be secured to one of such shafts and such sprocket may receive motion by means of a chain 45^d from a shaft 45^e projecting through the outer wall of the housing.

Within the carbonizing chamber 23^b, vertical series of guide rollers 48 and 49 are provided, such guide rollers serving to support the fabric in a series of horizontal runs extending upwardly from the lower part of the chamber to the plane of the opening 25.

Between certain of such runs, horizontally arranged steam coils 50 are provided to radiate heat directly against the surface of the fabric to raise the fabric to the carbonizing temperature. A secondary heating coil 51 may also be provided in the chamber 23^d to adjust the general temperature in this chamber, such coil being provided with a controlling valve 52 upon the outside of the casing if desired. Two or more of the rollers 48 may be provided with sprocket wheels such as 48^a and 49^a over one of which is trained a chain 52 which extends over a sprocket 53 upon the shaft of one of the rolls 45. A chain also extends upwardly from sprocket 49^a and over sprocket 48^a and from the latter sprocket a chain extends to a sprocket upon a shaft carrying the guide roll 25^b and from which the take-up roller 25^b may receive its motion.

The drying chamber between the partitions 26 and 27^a, it will be noted, is located between the plenum chamber and the economizer chamber so that its outer walls are at all times protected against rapid variations in temperature.

The material, upon entering the housing, passes over the guide rolls 44 and 45 in horizontal runs and at the same time the operation of the fan causes blasts of the heated air from the plenum chamber through the slots in tubes 46 everywhere to impinge on the surface of the fabric. Due to the arrangement of the parts, both sides of the fabric are subjected successively to the action of these heated blasts of fresh air, by which the moisture is rapidly and uniformly evaporated from the material and the latter is brought to a substantially dry condition prior to its entrance into the carbonizing chamber, which it enters in a hot, relatively dry state. In the latter chamber it moves upwardly, thus being subjected to a gradually increasing temperature in substantially still and dry air whereby the carbonization is effected in a certain and efficient manner, without serious loss of heat. The de-

sired temperature is thus maintained by the expenditure of vastly less steam than in prior practices. The heat of such chamber may be varied to a substantial degree by means of the controllable heating coil 51, so that the final temperature to which the material is subjected may be regulated with nicety. It will be noted that the carbonizing chamber is substantially an enclosed chamber. Provision may be made for the relief of temperature or pressure in this chamber, if desired, but usually the door 60, Fig. 2, suffices for the occasional necessity to open its enclosure.

The air expelled from the discharge nozzles 46 passes into the space 32 and from thence through the economizer 30 to the discharge pipe 34, while the fresh air entering the passage 35 passes in heat transferring relationship to the outgoing, vapor laden, and heated air in the tubes, so that the incoming air is heated to a substantial degree prior to its entrance into heating chamber 37. The device thus serves in an economical manner to dry and carbonize the material, permitting the amount of heat expended to be reduced to a minimum and at the same time, by the efficient application of heat to the material and the conservation of the heat in chamber 23^b, permitting the operation to take place at a lower radiated temperature than is common, so that the usual danger of damage by overheating is minimized. By the employment of suitable dampers in the inlet and outlet ducts, the temperature and moisture content of the air in the drying chamber may be nicely determined, such control being also facilitated by the employment of regulable heating coils in the heating chamber and by varying the speed of the fan.

The apparatus is compact in form, and since the main drying devices and the carbonizing chamber are entirely enclosed there is no discharge of injurious fumes into the space surrounding the apparatus.

While the process has been illustrated and described by reference to one specific embodiment of apparatus for carrying it into effect, it is to be understood that the process is independent of any particular apparatus and may well be practised without employing the apparatus here disclosed.

I claim:

1. That mode of finishing fabric which comprises as steps, moistening such fabric with a reagent, subjecting the fabric to a preliminary drying in the open air, and drying the fabric to a predetermined extent in a heat-insulated closed housing by subjecting the fabric to impinging blasts of air having a predetermined temperature and moisture content.

2. That mode of finishing fabric which comprises as steps moistening the fabric

120

125

130

- with a carbonizing reagent, drying the fabric in the open air at a temperature insufficient to cause evolution of fumes of the reagent employed, substantially completing 5 the drying in a closed chamber by the application of air blasts projected in a definite direction against the fabric, and carbonizing the fabric in a still atmosphere by the application of radiant heat.
- 10 3. That process of treating textile fabric which comprises subjecting such fabric to an acid bath, partially drying the fabric, and further drying the fabric in a closed housing by the application thereto of heated 15 blasts of air directed against its opposite sides, and thereafter subjecting the dried fabric to a carbonizing temperature.
4. That mode of finishing fabric which comprises as steps moistening the fabric 20 with dilute acid, partially drying the fabric in the open air at a temperature insufficient to evolve acid fumes, substantially completing the drying by repeatedly subjecting the fabric in a closed chamber to the action of 25 blasts of heated air directed against the surface of the fabric and thereafter subjecting the fabric to the action of still air at a carbonizing temperature.
5. That process of finishing textile fabric 30 which comprises passing such fabric through an acid bath, partially drying such fabric in the open air with the application of gentle heat, further drying such fabric in a closed heat insulated housing by the application thereto of heated blasts of air, and 35 subjecting such fabric to the direct action of radiant heat to raise it to a carbonizing temperature.
6. That continuous process of finishing fabric which comprises as steps moistening 40 the fabric with a carbonizing reagent, partially drying the fabric in the open air by the application of gentle heat, passing the partially dried fabric through a closed chamber and substantially completing the 45 drying of the fabric therein, and passing the fabric through a second closed chamber in a series of vertically spaced horizontal runs and applying radiant heat directly against the surface of the fabric while disposed in such horizontal runs. 50
7. That continuous process of finishing fabric which comprises drawing the fabric through a dilute acid bath partially drying the fabric in the open air, causing the fabric to pass through a closed chamber in a series of spaced substantially horizontal runs, projecting blasts of heated air against opposite sides of the fabric while disposed in such horizontal runs whereby substantially to complete the drying of the fabric, and passing the fabric through another closed chamber in a second series of horizontal runs, and subjecting the fabric to radiant heat of a carbonizing temperature 55 while disposed in said second series of runs. 60

Signed by me at New York city, N. Y., this 13th day of March, 1925.

JOSEPH H. WALSH.
